UNITED STATES PATENT OFFICE.

CHARLES UNION BREWSTER, OF OAKLAND, CALIFORNIA.

AUTOMATIC RULING-MACHINE.

932,676.

Specification of Letters Patent. Patented Aug. 31, 1909.

Application filed December 5, 1908. Serial No. 466,153.

To all whom it may concern:

Be it known that I, CHARLES UNION BREWSTER, a citizen of the United States, residing at Oakland, in the county of Alameda 5 and State of California, have invented a new and useful Automatic Ruling-Machine, of which the following is a specification.

My invention relates to improvements in machines for ruling a series of lines (of such 10 equal distance apart as may be desired, or of graduated distances, that is to say: Each line varies in distance from the preceding one in increasing or diminishing ratio as may be desired) on lithographic stones, metal plates 15 or in kindred processes or uses; and the objects of my improvement are:—a machine which runs by means of a motive power and performs its various functions automatically and without the necessity of personal attention. In the accompanying drawings I have 20 made use of a motive power, namely, electricity, for the purpose of full and intelligent demonstration of its automatic action. I attain these objects by the mechanism illustrated in the accompanying drawings, in 25 which:

Figure 1, is a perspective view of the entire machine. Fig. 2, is a top view of the machine. Fig. 3, is a vertical front view of 30 the entire machine. Fig. 4, is a vertical end view of the machine. Fig. 5, is a vertical end view of the reversing gear. Fig. 6, is a front sectional view of the bar or plate with the lifting and graduating mechanisms. 35 Fig. 7, is a top sectional view of the bar or plate with the lifting and graduating mechanisms. Fig. 8, is a perspective detail view of the reversing mechanism. Fig. 9, is a 40 sectional view of the actuating arm of the reversing mechanism.

Similar letters and numbers refer to similar parts throughout the several views.

The frame A on the legs B constitute the track upon which the traveling ways C move. On the ways C travels transversely the carriage D, suspended from which is the hanger E to which is pivoted the arm F with its counter-balance. Fastened firmly to the arm F is the apron G by means of which the

ruling point H fastened at the other end of 50 arm F is raised or lowered. The carriage D is moved on the ways C by means of the feed-screw I held in position by a collar K working in a bearing L with screw adjustment contained in the block J which is 55 fastened solidly to the ways C. This constitutes, practically, the regular mechanism employed in ruling machines at the present day.

The bar or plate 1, moves back and forth 60 on the bearings 2, 2, the length of motion being governed by the shoe 3 acting as a stop, said shoe 3 being moved by the feed-screw 3^a which is controlled by the bevel pinion 3^b and second bevel pinion 3^c, the 65 last mentioned pinion being connected solidly to the ratchet 4 having a handle attached thereto, said handle being used to alter the position of shoe 3 as desired. On the projecting hub of the ratchet 4, is the rocker- 70 arm 5, and on the said arm is the pawl 6, made to work either way as desired, and held in contact by a spring 6^a. On the extension of right-hand bearing 2 hangs 75 loosely the bar 7 which is connected at its other end to one of the holes in the rocker-arm 5 by means of a screw; a change in the holes making a change in the extent of movement of the rocker arm 5 and thus through the pawl 6, ratchet 4 and bevel pinions 3^b, 80 3^c, screw-threaded bar 3^a to the shoe 3, altering the position of said shoe 3 and thus the extent of movement of the bar or plate 1. The arm 5 and bar 7 constitute the graduating attachment and are used for this purpose only. A locking-finger 4^a holds the 85 wheel 4 solidly at any desired place for regularly spaced ruling.

At the back of the cross-piece of the ways C, are fastened two L shaped bars, 8 and 9, 90 which extend under the diagonally laid front bar of the frame A. A steel spring bar 10^a carrying the grooved wheel 10 at one end, is fastened to bar 8 as at 8^a and lies across bar 9 in which is a screw 9^a to apply tension to 95 the wheel 10, the purpose of which is to overcome the tendency to drawback of the ways C, caused by the movement of the bar or

plate 1 and the various movable parts actuated by or attached to the said bar or plate 1.

Running from a bearing in bar 9 to a bearing in the bar 11 suspended from the ways C at the back, is the bar 12, which is eccentrically hung, and said bar 12 being straight allows the apron G which rests against it to slide along as the carriage D is shifted. A short arm 13 is fastened to the eccentric bar 12 and held up by a spring 13^a, and is connected by a rod 13^b to one arm of the crank 14, the other arm of crank 14 carries the finger 15. The lifting plate 16 is chisel shaped at one end, and attached firmly to the bar or plate 1, but projecting beyond it sidewise, and bears and travels on the top of the cross-piece of the ways C; the said lifting plate 16 raising or lowering the finger 15 as it moves forward or back.

On top of bar or plate 1, is the rack 17 which meshes with the loose-running gear 18, projecting from which is the arm with pawl 19 that engages the ratchet 20 fastened solidly to the feed screw I.

Projecting from the cross-piece of ways C at either end, are the fingers 21, and fastened underneath ways C is the loose hung finger 22. Two bars, 23 and 24, moving freely in box-bearings, 25, 25, have movable thumbs 26, 26, and 27, with set-screws for fastening them securely to the said bars. The fingers 21, 21, move the bar 23 by means of contact with the thumbs 26, 26, and the finger 22 moves the bar 24 by means of contact with thumb 27. The right-hand end of bar 24 acts as a thrust to push the handle of knife-switch 28, and thus break connection with the motive power, the left-hand end of bar 23 has two fingers 23^a projecting from its side, between which freely plays the weighted rod 29 and as the bar 23 is thrust by the fingers 21 forward or back, it throws over the weighted rod 29 causing a reversing of the motive gearing.

The shoe 30 works freely on the ways C and is used to hold up finger 22 clear of thumb 27, and the shoe 31 also moves freely on the ways C, but has attached to it a rod 31^a traveling in a bearing 31^b on the carriage D, and held where desired by a screw in the said bearing 31^b.

The reversing gear consists of a standard 39, in a bearing in which runs the main shaft 32, and on the said shaft is a double frame 40 carrying a set of gears, one of which meshes with gear 33 fastened to said shaft 32. Above is a short shaft 34^a carrying gear 34, and having on its outside end a sprocket-wheel 34^b, both fastened solidly to said shaft, 60 and over the said sprocket-wheel travels the chain 41. The eccentric crank 35 works in a bearing in the standard 39, and is connected firmly to the arm 36 by means of a square joint and set screw. The other end 65 of the said crank 35 has a finger 35^a that

works in a slotted bearing 35^b in the double frame, for the purpose of throwing the said double frame first to one side and then to the other, causing first one of the gears and then the other to enmesh with gear 34 and thus reversing the motion of said gear 34.

Fastened to the sides of arm 36 at the top, is the band 37, equivalent to and used as fingers for the weighted rod 29, which is pivoted to the said arm 36 lower down, the space 75 between the said band or fingers allowing free play, for the purpose of avoiding a dead center. At the bottom of arm 36 projecting on either side, is the piece 38 bent at both ends to form stops or fingers which strike 80 the sides of the stand 39, first on one side and then on the other; the object of which is to prevent the gear from meshing too hard and causing vibration or jerking, the additional gears are merely used to vary the speed one 85 way from the other.

The action of the machine, starting at the extreme right-hand, is as follows: The power is applied by means of the shaft 32, and through gears, sprocket-wheel 34^b and chain 90 41, to the bar or plate 1 causing it to move to the left, this motion by means of the rack 17 turns gear 18 and through pawl 19 and ratchet 20 the feed-screw I, drawing carriage D forward transversely, at the same time the lifting-plate 16 raises the finger 15 and through 14 and 13 twists horizontally the eccentrically hung bar 12, forcing down the apron G and raising the ruling point H. The movement to the left continues until the shoe 100 3 strikes the left-hand bearing 2, causing the traveling ways C and all attached theron and thereto, to move to the left, until the left-hand finger 21 strikes the left-hand thumb 26 moving bar 23 to the left which 105 throws the weighted rod 29 over against the finger band 37, and through arm 36 and eccentric crank 35 moves the engaged gear in the double frame 40 out of contact with gear 34 and enmeshes the reverse which 110 starts the bar or plate 1 to the right. As the bar or plate 1 moves to the right and pawl 19 is running free on ratchet 20, bar 16 lowers finger 15 down the chiseled point, this movement through crank 14 and rod to the 115 short arm 13 causes the eccentric bar 12 to turn horizontally, allowing apron G to rise, this lowers the ruling point H. When the bar or plate 1 strikes the bearing 2 it causes the ways C and all attached thereon to move 120 to the right, drawing the ruling point across the surface, until the right-hand finger 21 strikes the right-hand thumb 26 moving bar 23 to the right and forcing the weighted rod over against the finger band 37, and through 125 the arm 36 and eccentric crank 35, moves the engaged gear in the double frame 40 out of contact with gear 34 and enmeshes the reverse gear and repeats.

The shoe 31 attached to the rod 31^a, is 130

held firmly by means of a set-screw in the bearing 31^b, at such a distance from the shoe 30 as is necessary to cover the desired width to be ruled, and as the carriage D is moved forward it gradually forces the shoe 30 along, until the loose-hung finger 22 is released and drops, on the next movement to the right the said finger 22 strikes the thumb 27 fastened to the bar 24, giving it a thrust and forcing 10 out of contact the knife switch 28, thus breaking the motive power connection, and the machine stops.

The rocker-arm 5 and the bar 7 are used for graduating only, and as the bar or plate 15 1 moves back and forth, they cause the bevel pinions 3^b and 3^c to turn by means of the ratchet 4 and pawl 6, thus causing the shoe 3 to move, forward or back, as the double pawl 6 may be set, thus altering the extent of 20 the distance of motion of the bar or plate 1, and by means of rack 17, gear 18, pawl 19 and ratchet 20, the feed-screw I, altering the space between the lines.

The double pawl 6 being set one way will 25 cause an increase in the distance of motion of the bar or plate 1, and also an increase in the distance between the lines, and when set the other way will cause a decrease. The connection of bar 7 with the different holes 30 in the rocker-arm 5, will cause a greater or less movement of said arm 5, and thus a corresponding variation in the space between the ruled lines.

I am aware that parts of this machine 35 have long been in use and although necessarily incorporated therein, my invention is additional thereto, and,

Having thus described my invention, what I claim and desire to secure by Letters Patent is:—

1. In a ruling machine of the character described, a main frame, ways mounted thereon, a carriage movable upon said ways transversely of the main frame, and means 45 whereby the carriage is moved, a bar or plate movable on bearings on the traveling ways, a shoe carried by said bar or plate having a feed screw, and means to regulate the extent of movement of said bar or plate.

2. In a ruling machine of the character described, a main frame, ways adapted to travel longitudinally thereon, a transversely movable carriage mounted upon said ways, a bar or plate, bearings upon which said bar 55 or plate travel, a shoe and feed-screw, a ratchet and double pawl whereby said screw may be fed either in or out, said pawl arm having a series of holes and a bar loosely attached at one end to the ways, and at the 60 other end to one of the holes in the said arm.

3. In a ruling machine of the character described, a main frame, ways mounted and adapted to travel longitudinally upon said frame, a transversely movable carriage 65 mounted upon the ways, a feed-screw and

actuating mechanism by which the carriage is moved upon the ways, an arm having a double pawl, a ratchet with which said pawl engages, a movable bar or plate, a traveling shoe, a feed-screw by which the length of motion of said bar or plate is determined, the movement of said bar or plate being varied automatically.

4. In an apparatus of the character described, a main frame, transverse ways movable longitudinally thereon, a carriage adapted to travel upon said ways, a hinged arm suspended from the carriage, a ruling point carried at one end of said arm, an apron at the other, a bar turnable in bearings upon the traveling ways, against which bar the apron rests and means to turn the bar, whereby the ruling point may be raised or lowered.

5. In an apparatus of the character described, a main frame, transverse ways 85 mounted thereon, a carriage movable upon said ways, a hinged arm suspended from said carriage, a ruling point at one end and an apron at the other end of said arm, bearings upon the ways, a bar turnably suspended 90 from said bearings against which bar the apron rests and by the eccentric movement of which the ruling point may be raised or lowered, and means by which the turnable bar is moved.

6. In an apparatus of the character described, a transversely movable carriage, a hinged arm suspended from said carriage, a ruling point carried at one end and a plate or apron at the other end of said arm, a finger and a lifting plate adapted to move beneath and raise said finger and to maintain it in the raised position, a crank arm actuated by said movement and a turnably hung bar to which said crank arm is connected, 100 said mechanism alternately raising and depressing the ruling point.

7. In a ruling machine, a main frame, ways adapted to travel longitudinally thereon, a carriage movable transversely upon 110 said ways, and a ruling point and adjusting mechanism supported from said carriage, means for transmitting motion to actuate said devices, means for shutting off the motive power, said means including rods or 115 bars having adjustable clamping devices, and fingers attached to the traveling ways adapted to engage the said rods or bars to reverse or cut off the movement.

8. In a ruling machine of the character 120 described, a main frame, ways traveling thereon, a carriage upon said ways, a ruling point and connecting mechanism suspended from said carriage, means by which the carriage may be moved transversely with 125 relation to the main frame, a movable finger, a shoe by which said finger is held up, a second shoe working upon the ways, a rod attached to said second shoe, bearings for said rod on the transversely movable car- 130

riage, said second shoe acting as a thrust against said first shoe holding up said finger, until the said finger is released, and means by which the said finger acts upon the said rod or bar to stop the movement of the mechanism.

9. In a ruling mechanism of the character described, a main driving shaft, a mechanism through which motion is controlled to rotate said shaft, a reversing mechanism, intermediate reciprocating mechanism through which a ruling point is actuated, a chain passing around sprocket-wheels on the shafts at opposite ends of the machine, and having its ends connected with the intermediate reciprocating mechanism, and devices actuated by said reciprocating mechanism whereby the movement of the apparatus is reversed after each reciprocation.

10. In an apparatus of the character described, a ruling mechanism, a main driving shaft, a mechanism by which power may be applied or cut off, a sprocket upon a shaft, a reverse gear mechanism, a sprocket carried thereby, a chain passing around said sprockets, and having its ends connected with the intermediate reciprocating mechanism, means by which the ruling mechanism is advanced transversely to the desired distance, and contact carried by the reciprocating mechanism adapted to disengage the power when the work is completed.

11. In a ruling apparatus of the character described, a main frame, transversely mounted ways movable thereon, a carriage and a suspended ruling point, said carriage being movable transversely upon the ways, means by which the ruling point is raised when moved in one direction, and depressed when moved in the opposite direction, said means including a reciprocating device and a bar carried thereby, a finger in the line of travel of the bar and adapted to be raised when the bar moves in one direction, and released when it moves in the opposite direction, a turnably mounted bar, a crank arm actuated by the finger to move said bar, and a plate actuated by the movement of the bar to alternately depress and raise the ruling point.

12. In an apparatus of the character described, a transversely movable carriage, a tilttable ruling point suspended therefrom, a screw, pawl and ratchet mechanism by which said screw is turned to advance the carriage, mechanism by which the ruling point is alternately depressed and raised, a reciprocating bar by which said mechanism is actuated, a stop shoe movable with relation to said bar, and means by which said shoe is adjusted to determine the length of stroke.

13. In a ruling apparatus of the character described, a transversely movable carriage and actuating mechanism therefor, a hinged ruling point carrier suspended from the car-

riage having a plate or apron carried upon its opposite end, a turnably suspended bar against which the apron is slideable as the carriage advances transversely, means for tilting said bar to act upon the apron and alternately raise and depress the ruling point.

14. In an apparatus of the character described, means for regulating the distance between the ruled lines, said means including a reciprocating screw-threaded bar, a shoe within which the bar is turnable, a bevel pinion on the screw-threaded bar, a rocker arm, a pinion moved thereby and engaging the first named pinion, a bar turnable on a fixed pivot, connections between the movable end of said bar and the rocker arm, and a pawl and ratchet mechanism actuated by the rocker arm.

15. In an apparatus of the character described, means for regulating the distance between the ruled lines, said means including a reciprocating screw-threaded bar, a shoe within which the bar is turnable, a bevel pinion on the screw-threaded bar, a rocker arm, a pinion moved thereby and engaging the first named pinion, a bar turnable on a fixed pivot, adjustable connections between the movable end of said bar and the rocker arm, and a pawl and ratchet mechanism actuated by the rocker arm.

16. In an apparatus of the character described, and moved by power, a reversing mechanism, a standard or hanger, a bearing in said standard or hanger in which revolves a constantly moving direct power shaft, a gear fastened thereto, a double frame bearing on said shaft at either side of said gear, said double frame being held in an upright position and moved from side to side by a finger eccentrically placed on a crank, a crank turnable in a bearing in the said standard or hanger, said crank having a finger projecting therefrom at one end and moving eccentrically as the said crank is turned, the said finger working in a slotted bearing in the said double frame, a set of gears working on shafts connected with and fastened to the said double frame, one of the said gears being continuously engaged with the gear on said direct power shaft and transmitting motion in opposite directions to two other gears in said double frame, a short shaft above the said double frame, said shaft working in bearings in said standard or hanger, and carrying a sprocket wheel at one end, and a gear so set as to engage alternately with the said gears that travel in opposite directions in the said double frame when the said double frame is shifted by means of the said eccentric crank finger, an arm fastened to said eccentric crank, a rod pivoted to said arm, a weighted ball at the other end of said rod, said rod having free play between a band fastened at the oppo-

115
120
125
130

site end of said arm to which it is pivoted, the contact of the said rod causing the said crank to turn, and the turning of said crank forcing the said double frame to shift, thus causing the gear in the double frame that is engaged with the gear on the said upper shaft, to be disengaged, and the other one of said gears which is traveling in the opposite direction, to be engaged in its place, thus reversing the motion of said short shaft carrying the sprocket wheel. 10
